UNITED STATES PATENT OFFICE.

CHARLES D. HARRINGTON, OF SOUTHBIDGE, MASSACHUSETTS, ASSIGNOR TO HARRINGTON CUTLERY COMPANY, OF SOUTHBIDGE, MASSACHUSETTS, A CORPORATION OF MASSACHUSETTS.

BOX-SEAL.

1,097,019.

Specification of Letters Patent.

Patented May 19, 1914.

Application filed February 12, 1912. Serial No. 676,960.

To all whom it may concern:

Be it known that I, CHARLES D. HARRINGTON, a citizen of the United States, residing at Southbridge, in the county of Worcester and State of Massachusetts, have invented certain new and useful Improvements in Box-Seals, of which the following is a specification.

My invention relates to improvements in boxes, and has for its leading object the provision of novel and improved means for securing together the two sections of a box of the telescopic type in which one section of the box fits within the other section thereof.

15 The further object of my invention is the provision of an improved seal for this purpose which shall be so constructed as to be ready of application and inexpensive of construction and which while permitting of the ready opening of the box in the correct manner, will prevent persons casually handling the box from readily opening the same.

Another object of my invention is the provision of an improved box seal which may be utilized to hold the two portions of the box together at one end in order that the cover and containing portions of the box may not become separated and thus confusion result due to mixing of the various 30 covers for boxes containing different prices of articles as frequently occurs when the covers are entirely loose and separate from the boxes.

Other objects and advantages of my improved box seal will be readily apparent by reference to the following description taken in connection with the accompanying drawings, and it will be understood that I may make any modifications in the specific structure shown and described within the scope of the appended claim without departing from or exceeding the spirit of my invention.

Figure I represents a bottom plan view of a box secured with my improved seals. Fig. II represents a longitudinal sectional view thereof on line II-II of Fig. I. Fig. III represents a similar sectional view illustrating a slightly modified application of my seal, and Fig. IV represents a sectional view of a further modification of my invention showing the use of my seal as a hinge for connecting the two portions of the box.

In the drawings, in which similar characters of reference are employed to denote corresponding parts throughout the several views, the numeral 1 designates the top of the cover section which is provided with the depending side and end sections 2 which form a peripheral flange for receiving the upwardly projecting sides and ends 3 of the bottom 4 of the box, the length of the portions 2 and 3 being approximately equal. In use the portions 3 resting against the under side of the cover. I am aware that previous to my invention other means have been employed for sealing boxes of this type and that it is not new to hold the two sections of the box together by placing over the lower edge of the flange 2 and the adjacent portion of the bottom of the box a strip of material which will connect the top and bottom and which may be cut or severed to permit of separation of the parts. This method of securing the top and bottom together possesses decided disadvantages in that when a box so sealed is handled frequently the said connection material is liable to become torn or worn through so as to permit of its rupture when the cover is grasped to lift the entire box. Another disadvantage of this method of sealing is that when a box so sealed is placed on a counter for advertising purposes or when a salesman is hunting for a certain article upon the shelves the said box may be readily opened by cutting the connecting member with the finger nail and this will permit of the unnoticed abstraction of a portion of the contents of the box or will cause an unnecessary number of boxes having the same contents to be opened and increase the difficulty of the store keeper keeping track of the amount of goods which he has in stock. It is the purpose of my invention to obviate these various objectionable features and to do this in the form of my invention shown in Fig. II, I have secured to the inner face of the end portions 2 of the cover the strip 5, which may be of either paper or cloth and of any desired strength according to the weight of the contents of the box. This strip 5 has the end 6 secured to the cover and is then provided with a free portion 7 terminating in a lower end 8 which is placed against and is secured to the bottom of the

box. In the drawings I have illustrated the seal as disposed at the ends of an oblong box as it best receives the strain and resists opening of the box by separating tension 5 exerted against the bottom and cover, although it will be understood that the seal may be placed at any desired point.

In Fig. III, I have shown a slight modification of my seal as regards the manner in 10 which the same is attached to the basal section of the box, in that the same is secured not only to the bottom 4, but to the adjacent portion of the end section 3, thus preventing the loose portion of the member 5 from 15 being at the very bottom of the box where it might be cut by the finger nail, and causing said loose portion 7 to be disposed high enough within the space between the end portions 2 and 3 to necessitate the using of 20 a knife or similar implement.

In Fig. IV, I have shown a still further modification of the method of attachment of my improved seal 5, in this view the attached portion 6 being secured to the under 25 side of the top 1, while the other end is secured to the under side of the bottom 4 of the box, thus providing the longest loose portion 7 and making the most satisfactory hinge connection between the top and bottom, since it permits of the greatest relative movement of the two portions at one end when the other end has been loosened 30 without tearing or pulling loose of the seal.

From the foregoing description taken in 35 connection with the drawings the construction of my improved box seal will be readily understood, and it will be seen that I have provided a seal which has one end secured to the cover section of a box and the other 40 end to the bottom of the box, while the intermediate portion of the said seal is free and extends diagonally between the top and bot-

tom in such manner that a tool or implement inserted between said portions will serve to sever the seal to permit of opening 45 of the box while the box cannot be readily opened merely by the finger nail, and consequently is more free from tampering with by unauthorized persons than is the case with boxes sealed in the ordinary manner. 50 It will also be observed that the loose portion 7 has a second advantage, in that the top and bottom may have slight relative play so that undue forcing together of said portions does not tear loose the seal, or 55 slight relative sliding of the parts does not tear the seal, while when one end of the box has been unsealed the cover and bottom may be shifted relative to each other to permit of removal of all or a portion of the 60 contents of the box, the portion 7 serving as a hinge and preventing separation of the top and bottom so that the top with its designations as to quality and price of the goods is 65 always with the box containing the said goods.

I claim:

The combination with a box comprising two telescopic sections, a severable seal therefor, one end of said seal being secured 70 to the cover near the top thereof and the other end secured to the bottom of the box, the seal having an intermediate portion extending diagonally between the overlapping portions of the box whereby the seal is protected and concealed by the sections of the 75 box.

In testimony whereof I affix my signature in presence of two witnesses.

CHARLES D. HARRINGTON.
